UNITED STATES PATENT OFFICE

OTTO H. HARTMANN, OF KASSEL-WILHELMSHOHE, GERMANY, ASSIGNOR TO SCHMIDT'SCHE HEISSDAMPF-GESELLSCHAFT MIT BESCHANKTER HAFTUNG, OF KASSEL-WILHELMSHOHE, GERMANY

INTERSTAGE STEAM SUPERHEATING BY MEANS OF HIGH-PRESSURE STEAM

Application filed June 5, 1928, Serial No. 283,055, and in Germany July 2, 1927.

My invention relates to apparatus for reheating interstage steam in power plants by means of high-pressure steam. In such arrangements, it has been usual hitherto either 5 to allow the condensate from the heating steam to flow back under gravity to the high-pressure boiler or to provide a special pump for its return. In the first case it is necessary, in order to obtain the necessary fall, to instal 10 the reheat at such a height that in stationary plants the appearance of the engine room suffers. In portable installations, on the other hand, for example, locomotives and traction engines, in view of the limited height available, it is out of the question to instal 15 the reheat at the necessary height. In the second case, it is desirable when possible to avoid the use of a pump for returning the condensate, on account of first cost, maintenance charges and working difficulties. 20

In order to overcome the above difficulties, my present invention consists in leading back 25 the condensate of the heating steam for the reheat into a vessel or container at a lower pressure. The admission of the condensate into the vessel at a lower pressure can be controlled by some form of throttle device, or by 30 a steam trap or the like, while the vessel or container itself can be inserted in the circulating system of the boiler feed-water.

In multi-pressure boiler installations, the condensate of the heating steam is preferably 35 returned to a boiler section working at a lower pressure, or if the installation is provided with multi-stage feed-heating, the condensate may be led to one of the hotter of such stages.

Various advantages arise from my present 40 invention. In the first place, from the point of view of thermal efficiency, the heat still present in the condensate of the heating steam is not lost but is usefully applied to the pre-heating of the boiler feed-water or to the heating of the water in the boiler itself. In 45 addition, the use of a condensate pump is eliminated and it is possible to arrange the reheat in the foundations in the case of a stationary installation, and below the boiler itself in the case of a locomotive.

50 The accompanying drawings show by way

of example several forms of construction of the invention.

Figure 1 shows the arrangement as applied to an indirectly heated two-pressure marine installation, the two-pressure boiler being 55 shown in longitudinal section;

Figure 2 is a cross-section on the broken line II-II of Figure 1;

Figure 3 is a longitudinal section of a two-pressure locomotive; 60

Figure 4 is a plan view of the arrangement of the cylinders and the reheat, partly in section.

In the marine installation shown in Figures 1 and 2, the high-pressure steam is generated according to the indirect method in the upper working drum 1, by means of a heat carrier which circulates in a closed tube system and gives up its heat to the water in the working boiler by help of heating elements 2, arranged in the drum 1. The heat-receiving part of the circulating tube system for the heat carrier consists of tubes 3, forming the furnace flue, which are connected at their lower ends to collector headers 4, and 70 at their upper ends to distributor headers 5. The latter, by means of risers 6, and the former by downcomers 7 are connected to the heating elements 2. The high-pressure steam generated in the boiler 1 is led by way 75 of a pipe 8, fitted with a shut-off valve 23' through the superheater 10, arranged in the reversing chamber 9 of the boiler installation, to the high-pressure stage 11 of the engines, and after expansion therein exhausts 80 through a pipe 24 to the intermediate stage 12; the exhaust from the latter stage is led through a pipe 13 to a reheat 14, from which the steam passes through a pipe 15 to the low-pressure stage 16 of the engines and thence through a pipe 25 to the condenser 23. The condensate is sucked by a pump 26 through a pipe 27 and delivered through a pipe 28 to a hot water well 29 of known construction, from which it is taken by a feed water pump 30, and delivered through a pipe 31 to the low-pressure boiler 22. A feed water pump 33 takes a portion of the water contained in the boiler 22, through a pipe 34, 100

and delivers it to the high-pressure drum 1 through a conduit 35.

For reheating the interstage steam in the reheater 14 high-pressure and highly-superheated live steam is used, which is taken from the steam delivery pipe 17 from the superheater 10 through a branch pipe 18, leading to a serpentine or coil 19, in the reheater. The condensate of this heating steam 10 is led by way of a steam trap 20, a throttle valve or the like and a pipe 21 into the water space of the smoke-tube boiler 22, serving as the low-pressure section of the installation and arranged in series with the high-pressure boiler as regards the flue gases. As 15 a lower pressure rules in this boiler than in the high-pressure boiler, the condensate of the heating steam flows to the low-pressure boiler without the need of a pump. The low-pressure steam passes from the boiler 22 through a conduit 37, provided with a valve 38, to the superheater 36, arranged in the smoke tubes of the boiler 22, and from the superheater 36 through a pipe 39 to the pipe 24 where it is mixed with the exhaust steam 25 from the high pressure stage and passes to the second stage of the engine.

In the locomotive shown in Figures 3 and 4 the same reference symbols are used to denote 30 corresponding parts. The exhaust steam from the high-pressure cylinder 11 is led through a pipe 13 to the reheater 19, from which it passes through conduits 15 to valves 40, where it is mixed with the superheated 35 low-pressure steam coming through pipes 39 from the low-pressure superheater 36. This steam mixture passes from the valves 40 to the low-pressure cylinders 16. The exhaust steam from the cylinders 16 passes through 40 conduits 41 to the blast pipe 42. The condensate of the heating steam is led from the heating coil 19 of the reheater by way of a steam trap 20 through a pipe 21 fitted with a valve 43 to the smoke tube boiler 22.

45 For enabling the reheating of the exhaust steam of the high-pressure stage of the engine by means of high-pressure saturated steam a branch pipe 44 leading to the interstage superheater 19 and fitted with a valve 45 is 50 connected with the pipe 8 conveying the live steam from the high-pressure drum 1 to the high-pressure superheater 10.

I claim:

1. In a steam power plant, a multistage 55 engine, a boiler generating high pressure steam, a boiler generating low pressure steam, a superheater, means for conducting steam from the high pressure boiler through the superheater to the first stage of the engine, 60 means for conducting steam from the low pressure boiler to a stage of the engine other than the first, a reheater, means for conducting the exhaust from said first stage of the engine through the reheater to a stage other 65 than the first, means for conducting high

pressure steam from said high pressure boiler to said reheater to act as a heating medium therein, and means for conducting the condensate of said high pressure steam formed in said reheater to said low pressure boiler.

2. In a steam power plant, a multistage engine, a boiler generating high pressure steam, a boiler generating low pressure steam, means for conducting steam from the high pressure boiler to the first stage of the engine, means 70 for conducting steam from the low pressure boiler to a stage of the engine other than the first, means for conducting the exhaust from one stage of the engine to a later stage, said last named means including a reheater, means for conducting high pressure steam from said high pressure boiler to said reheater to act as a heating medium therein, and means for conducting the condensate of said high pressure steam formed in said reheater to said low pressure boiler.

In testimony whereof I affix my signature.

OTTO H. HARTMANN.
